UNITED STATES PATENT OFFICE.

ZENAS P. CANDEE, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

MULTIPLE-PLUNGER MACHINE.

Application filed May 20, 1920. Serial No. 383,004.

To all whom it may concern:

Be it known that I, ZENAS P. CANDEE, a citizen of the United States, residing at Waterbury, in the county of New Haven and 5 State of Connecticut, have invented certain new and useful Improvements in Multiple-Plunger Machines, of which the following is a specification, reference being had therein to the accompanying drawings.

10 My invention relates to a new and improved multiple plunger machine wherein a plurality of plungers, or gates carrying punches or similar tools, are used in conjunction with corresponding dies or tools 15 suitably held.

It is the object of this invention, among other things, to operate the several plungers or gates from a single crank shaft; to so construct the ways for the plungers or gates 20 that they may be completely machined and assembled outside of the body of the machine and then as a unit assembled therewith, and thereafter each of the ways for the separate plungers be independently removed and adjustable as well as the plungers themselves; and further to provide means whereby the 25 relative endwise position of the plungers may be independently varied and separately adjusted.

30 To these, and other ends, my invention consists in the multiple plunger machine having certain details of construction and combinations of parts as will be hereinafter described and more particularly pointed out 35 in the claims.

Referring to the drawings in which like numerals of reference designate like parts in the several figures.

Figure 1 is an elevation of my new and improved mechanism shown assembled with such portion of the body of the machine and adjacent parts as are essential to a disclosure of its construction and operation.

Figure 2 is an enlarged sectional view 45 thereof taken substantially upon line 2—2 of Figure 1.

Figure 3 is a sectional plan view of a portion thereof taken upon line 3—3 of Figure 2.

50 Figure 4 is a detailed view of one of the sections of the eccentric sleeve.

Figure 5 is a fragmentary plan view of the way frame and adjacent parts.

Figure 6 is a fragmentary elevation

thereof, and Figure 7 is an enlarged elevation of the eccentric sleeve.

Heretofore it has been the general practice to operate the several plungers or gates of a multiple plunger machine by means of cams, toggles or similar mechanism.

In my new and improved machine I am able to operate a plurality of independent plungers or gates from a single crank shaft, each of these plungers being independent of each other, operated in independent ways 65 and separably removable and adjustable.

The form or shape of the body of the machine to which my invention is applied is not material, but I have shown in the drawings one of such forms wherein the numeral 10 70 designate the machine, which is of the press type, having parallel portions connected at one end by a bed 11 and at the other end by a head portion 12 and within which is journaled a crank shaft 13. This crank shaft is 75 shown as having three cranks 42, but a greater or less number may be used as desired and on each side of each of the cranks are cheek portions 14. The two intermediate cheek portions are journaled in the bearings 80 15, providing a support for the crank shaft between its main journals in the machine 10.

The means for pivotally connecting each of the plungers or gates 16 with the crank of the crank shaft 13 comprises the connection 17, cap 18 secured thereto by screws 19 or similar means, eccentric bushing 20, swivel block 39 hinged to the plunger 16 on the swivel pin 40 and secured to the connection 17 by the key 41. By removal of this key 41 90 the plunger 16 and the swivel block 39 therewith are separated from the connection 17.

The bushing 20 is constructed of two sections, the side elevation of one of which is shown in Figure 4, having an opening 21 95 therethrough of the same diameter as the cranks 42, with its outer surface 22 eccentric therewith, and provided with a flange 23 at one end. For convenience in machining and assembly a tongue and groove joint 24 is 100 provided to insure a proper alignment of each of the sections in relation to the other. In the periphery of the flange 23 are a plurality of holes 25 into which a rod (not shown) is inserted for the purpose of rotating the eccentric bushing 20 about the axis of the crank 42.

The outside diameter of the bushing 20 is

the same as the bore in the connection 17 and cap 18 and when inserted therein, as shown, is held against relative movement by the frictional engagement of these parts therewith.

5 In assembling the bushings 20 are placed on the shaft as shown in Figure 1, the outer faces of the flanges 23 preferably in contact with or adjacent to each other and their opposite ends adjacent to the cheeks 14 of the crank shaft. After the bushings are located, the connections 17 are placed in position and the caps 18 secured thereto, at which time the bushings, connections and caps all form 10 one unitary structure.

15 To vary the relative position of the connections 17 and the cranks, the eccentric bushing 20 is moved about the axis thereof and when the desired position is obtained the 20 parts are then again secured together by manipulation of the nuts 19 and the connection operates in its new relative position. This adjustment provides for a limited variation in the position of the gate 16.

25 I am able by the means above described to operate the several gates from a crank shaft, the mechanism for connecting the same being comparatively simple and readily assembled and each gate is operated independently 30 of every other gate. Its relative position in relation to the crank may be varied at will without regard to any other gate and the shaft itself is rotatably supported and mounted so as to withstand the greatest pressure put upon it through the operation of the tools in the gate.

35 Secured within the machine 10 by screws 26, or other suitable means is a way frame 27 provided with a plurality of recesses 28 corresponding in number with the plungers 16 and secured to the sides 29 of this way frame near the top and bottom thereof, by bolts 30, or similar means, are the plates 31 having recesses 32 therein which are opposite to the recesses 28 and within which are connected the ways 33 between which the gates 16 are movably mounted.

40 The ways 33 associated with the way frame 27 are secured thereto by the screws 34 and the ways 33 associated with the plates 31 are adjustably secured therein by the bolts 35 and held in their adjusted positions by the screws 36. To vary the in and out position of the ways just referred to, the screws 55 36 are loosened and the way brought to its new position through manipulation of the screws 35 and is there held with the ends of the screws 36 impinging against the face of the ways. By this means of holding the 60 ways, their position may be varied to take up wear and by releasing the screws 35 therefrom without disturbing the screws 36, the ways can be removed and returned to their former position without further adjustment.

In order that the plates 31 may be entirely rigid in relation to the frame 27, I find it desirable in some cases to use the spacing studs 37 which are screwed into the frame 27 at one end and are engaged by the bolts 70 38 at the other end that pass through the plates 31 and are threaded into the studs. By this method of constructing and mounting the ways they may be completely machined, as well as the frame that holds them, 75 outside of the machine 10. This will very much reduce the cost of construction and facilitate the assembly of the parts with exactness and nicety before being placed in the machine itself. Again if it is desired to 80 take out any one of the ways, it is only necessary to release the screws 35 therefrom and then allow the way to drop out, or if the space below the lower plate is not sufficient to permit this, the latter can be removed, 85 and the way dropped a sufficient distance to allow the top thereof to pass under the upper plate 31, or if the space is so contracted as not to admit this endwise movement both plates 31 may be removed and the way taken 90 out without endwise movement. Obviously like the ways the plungers or gates 16 may also be removed separately as may be desired.

95 There are minor changes and alterations within my invention aside from those herein suggested and I would therefore have it understood that I do not limit myself to the exact construction herein shown and described but claim all that falls fairly within 100 the spirit and scope of the appended claims.

Having described my invention what I claim as new and desire to secure by Letters Patent, is:

1. In a device of the character described 105 the combination with a machine body; of a rotary element; a plurality of plungers; ways for said plungers; a frame removable from said body member for supporting said ways; means for mounting each of said ways 110 in said frame whereby the same are independent of each other; and means for operating said plungers from said rotary element.

2. In a device of the character described 115 the combination with a machine body; of a rotary element; a plurality of plungers; ways for said plungers; a frame removable from said body member for supporting said ways; means for adjustably and separably securing said ways to said frame; and means 120 for operating said plungers from said rotary element.

3. In a device of the character described 125 the combination with a machine body; of a rotary element; a plurality of plungers; a pair of ways for each of said plungers; a frame; means for mounting said pairs of ways in said frame whereby one of each of said pairs of ways are connected with members removable from said frame; means for 130

removably supporting said frame in said body member; and means for operating said plungers from said rotary element.

4. In a device of the character described
5 the combination with a machine body; of a rotary element; a plurality of plungers; a frame removably connected with said body member; one or more plates connected with said frame; a pair of ways for each of said
10 plungers, one of the ways in each of said pairs being connected with said frame, and the other with one of said plates; and means for operatively connecting said plungers with said rotary element.
- 15 5. In a device of the character described

the combination with a machine body; of a rotary element; a plurality of plungers; a frame removably connected with said body member; a pair of ways for each of said plungers; means for securing one way of 20 each pair of ways to said frame; means for adjustably securing the other of the ways of each of said pairs to parts removably connected with said frame, and means for operating said plungers from said rotary 25 element.

In testimony whereof, I have hereunto affixed my signature.

ZENAS P. CANDEE.
